(57) **CLAIM**

The ornamental design for a shirt, as shown and described.

DESCRIPTION

FIG. 1 is a front perspective view of a shirt showing our new design in an in-use configuration;

FIG. 2 is a front view thereof;

FIG. 3 is a rear view thereof;

FIG. 4 is a side view thereof; and,

FIG. 5 is a second side view thereof.

The broken lines immediately adjacent to the shaded area represent unclaimed boundaries of the design. The unshaded regions, demarcated by broken lines, represent portions of the shirt that form no part of the claimed design. The pattern of circles represents the appearance of mesh. The broken lines showing the remainder of the shirt represent unclaimed subject matter and form no part of the claimed design.
